UNITED STATES PATENT OFFICE.

CHARLES R. WILLIAMS, OF GEORGEL, VIRGINIA, ASSIGNOR OF ONE-FOURTH
TO C. W. SHAFFER, OF LANDGRAFF, WEST VIRGINIA.

MINE-CAR CHECK-HOLDER.

SPECIFICATION forming part of Letters Patent No. 634,049, dated October 3, 1899.

Application filed November 30, 1898. Serial No. 697,907. (No model.)

To all whom it may concern:

Be it known that I, CHARLES R. WILLIAMS, a citizen of the United States, residing at Georgel, in the county of Wise and State of Virginia, have invented a new and useful 5 Mine-Car Check-Holder, of which the following is a specification.

My invention relates to a check-holder and display device for use in connection with 10 mine-cars; and the object in view is to provide a holder of such a construction that when a number or identifying-check, such as those employed by miners to designate cars containing material for which they desire credit, 15 is placed therein the surreptitious or fraudulent removal or substitution of the check is prevented and the check which has originally been placed therein is released only when the car reaches the tipple and is thrown into a 20 discharging position.

When a miner, as A, is about to commence work, he is furnished by the office with a number of checks bearing corresponding numbers or designating characters different from those 25 of the checks furnished other miners, and this character is credited, with the name of the miner, on the books of the office, and each car of coal or other mined material filled by A is designated by attaching thereto one of 30 these identifying-checks, whereby when the car reaches the surface the tipple-man or the person employed for that purpose notes the check on the car and credits the miner designated by that check with one car-load. Ordinarily each car is provided inside and at a 35 point below the upper edges of its walls with a hook, upon which one of these checks is hung before the car is filled, whereby when filled the coal or other material covers the 40 check, with the object that the car must be emptied to discover the check. Dishonest miners, however, surreptitiously gaining access to a filled car having the check of another miner attached thereto displace enough 45 of the contents of the car to discover the check and substitute his own, as that of B, for the previously-attached check of A, whereupon when the car reaches the surface B receives the credit for the car-load, this fraud usually 50 being perpetrated during rest-hours, as at night. The fact of the substitution is not obvious upon viewing the car, for the reason

that the check is covered by the contents of the car and is invisible, and therefore A, having left a full car in the mine at the close of 55 working hours on one day, does not discover the next day upon entering the mine that his check has been displaced and that of another miner has been substituted.

The object of my invention is to provide a 60 check-holder from which a check cannot be displaced except by tipping the car, as in the act of discharging its load, and also of such construction that a check arranged therein is visible, whereby the miner upon returning to 65 the mine after having previously left a filled car can by a glance ascertain whether his check is still in place as when he left the car.

A further object of the invention is to provide a check-holder of such a construction 70 that a check cannot be concealed by a second check introduced thereto.

Further objects and advantages of this invention will appear in the following description, and the novel features thereof will be 75 particularly pointed out in the appended claims.

In the drawings, Figure 1 is a view of a check-holder constructed in accordance with my invention applied in the operative position to a mine-car, the latter being in its normal or upright position. Fig. 2 is a view of the holder in the position which it occupies when the car is tipped. Fig. 3 is a view of the holder with its face-plate partly broken 85 away to discover the channels and receptacles for the check. Figs. 4 and 5 are detail sections taken, respectively, in the planes indicated by the lines 4 4 and 5 5 of Fig. 3 through the removal-seat of the holder. Fig. 90 6 is a section taken upon a plane indicated by the line 6 6 of Fig. 3 through the disclosure-seat of the holder. Fig. 7 is a detail view of a check such as those ordinarily employed in connection with mine-cars. Fig. 8 95 is a perspective view of the holder detached from the car.

Similar reference characters indicate corresponding parts in all the figures of the drawings.

The holder embodying my invention consists of a casing or receptacle, preferably constructed of front and rear plates 10 and 11, in one of which, preferably the latter, is

formed a sinuous channel 12, extending downwardly from an inlet or receiving opening 13 to a disclosure-seat 14. The upper portion 12^c of this channel adjacent to the inlet-opening 13 may be vertical, as indicated in the drawings, and this is connected by a downwardly and inwardly inclined portion 12^b with a second downwardly and outwardly inclined portion 12^c, which terminates in the disclosure-seat 14, a wedge-shaped deflector or guard 15 being interposed between the communicating inclined portions 12^b and 12^c to prevent a wire or other instrument inserted through the opening 13 from reaching the disclosure-seat. The lower wall of the channel portion 12^c is deflected or diverged from the upper wall thereof and is preferably arranged at such an inclination to a horizontal plane as the car to which the holder is attached usually receives when upon the tipple or is in dumping position, whereby when the car is inclined said lower side of the channel portion 12^c will be inclined downwardly and inwardly, as indicated in Fig. 2, to its point of communication with an outlet-channel 16, terminating in a removal-seat 17. The check 18, which is usually employed as a designating device in mines, consists of a disk having a number or other character stamped thereon, and when the holder is in its upright or normal position, as indicated in Figs. 1 and 3, the check after being introduced at the opening 13 will pass through the length of the channel 12 and will rest finally in a disclosure-seat 14, where it is visible through an inspection-pane 19, let into a suitable opening in the front wall of said seat, as in the front or face plate 10, and the depth of the channel is such as to correspond 40 approximately with the thickness of the disk, whereby a second check, subsequently introduced into the channel, may not pass between the first check and the inspection pane or opening, but will strike against the first check, as indicated in dotted lines in Fig. 3, and will there be held out of view through the inspection-opening. The check is prevented from dropping into the removal-seat 17 or from gaining access to the inlet-channel 16 by a deflector 20, which projects inwardly between the upper end of the channel portion 12^c and the communicating end of the outlet-channel 16, the extremity of said deflector 20 overhanging the point 21, which separates the channel portion 12^c from the outlet-channel 16 at the lower side; but when the car is tilted to discharge its contents the lower wall of the channel portion 12^c, leading from the disclosure-seat to the outlet-channel 16, is inclined downwardly toward the latter, as indicated in Fig. 2, thereby causing the check to traverse said lower wall of the channel portion 12^c and pass into the outlet-channel, which in turn is traversed 55 until the check reaches a position in the removal-seat 17. The front wall or face-plate of the casing or receptacle is provided with a

finger-slot 22 in alignment with the outlet-channel 16 and intersected by a transverse slot 23, the floor of the removal-seat being 70 grooved, as shown at 24, to facilitate the removal of the check by pressing rearwardly upon one edge of the check to throw the other edge forward into the transverse slot 23. Also the upper and lower walls of said transverse slot 23 are preferably beveled and undercut, respectively, to facilitate the removal of the check. The finger-slot 22, however, is preferably made of such a length as to disclose the occupancy by the removal-seat of a 80 plurality of checks, and therefore if a fraudulently inclined person has introduced a second check into the holder the tilting of the car will cause both checks to pass into the outlet-channel 16, and both will be visible 85 through the finger-slot 22; but it is known that of two checks thus arranged in the holder the upper one is that which was first introduced into the holder, the relative positions of the checks being reversed by the tilting 90 operation to cause that check last introduced into the holder to occupy a position at the lower end of the removal-seat 17. Owing to the fact that displacement or removal of a check introduced into the holder 95 cannot be accomplished fraudulently or by any other means than by tilting the car to cause it to pass into the removal-seat, and as the interposition of a second check between the first check and the inspection-pane is prevented by the depth of the channel corresponding approximately with the thickness 100 of the check, it will be seen that the fraudulent substitution of checks, as in the old practice, is prevented by an apparatus having the 105 essential features of the holder herein disclosed.

To exclude dust from the material of the holder, I preferably provide its inlet-opening 13 with a movable cap or cover 25, pivotally mounted and provided with front and rear flanges to close down over the upper edges of the front and rear plates constituting the casing or receptacle.

It will be understood, furthermore, that 115 while in the drawings I have illustrated a simple form of holder adapted to be manufactured at a comparatively small cost the exterior contour and even the relative arrangement of the channels may be modified, 120 provided the relation is such as to guide a check when the holder is in its upright or normal position to an initial or disclosure seat or pocket, where it must remain in opposition to all attempts to displace it until the 125 holder is tipped to occupy an adjusted position by the discharging movement of the car, and also that various other changes in the form, proportion, and the minor details of construction may be resorted to without departing from the spirit or sacrificing any of 130 the advantages of the invention.

Having described my invention, what I claim is—

1. A mine-car having an attached check-holder provided with a check-seat, from which a check may be dislodged by the movement of the car to a discharging position, and having means for preventing dislodgment when the car is in its normal position, substantially as specified.
2. A tally-check holder for tilting receptacles, having a depressed check-seat accessible to a check when the holder is in its normal position, and from which a check may be dislodged when the holder is in a tilted position, and having means for preventing removal of the check when the holder is in its normal position, substantially as specified.
3. A tilting check-holder for the purpose named, having a check-seat with which communicates a sinuous inlet-channel, to guide a check to said seat when the holder is in its normal position, and an outlet-channel, accessible to the check when the holder is in a tilted position, substantially as specified.
4. A tilting check-holder for mine-cars, having a check-seat with which communicates a downwardly-accessible sinuous inlet-channel, to guide a check to said seat when the holder is in its normal position, and an outlet-channel, accessible to the check when the holder is in a tilted position, and a movable cover normally closing the inlet-channel, substantially as specified.
5. A check-holder for the purpose named, having an interiorly-visible check-seat with which communicate channels to guide a check to and from said check-seat, respectively, when the holder is in different positions and having means for preventing removal of a check when the holder is in one position, substantially as specified.
6. A check-holder for the purpose named, having a check-seat with which communicate inlet and outlet channels, for guiding a check to and from the check-seat when the holder is respectively in different positions, said outlet-channel terminating in a removal-seat from which a check may be displaced and which is constructed to temporarily hold the same, substantially as specified.
7. A check-holder for the purpose named, having a check-seat with which communicate inlet and outlet channels, for guiding a check to and from the check-seat when the holder is respectively in different positions, said outlet-channel terminating in a removal-seat in an exposed wall of which is formed a finger-slot, substantially as specified.
8. A check-holder for the purpose named, having a check-seat with which communicate inlet and outlet channels, for guiding a check to and from the check-seat, when the holder is respectively in different positions, said outlet-channel terminating in a removal-seat in an exposed wall of which is formed a finger-slot, and in the floor of which is formed a depression for facilitating the tilting of a check, substantially as specified.
9. A check-holder for the purpose named, having a check-seat and communicating inlet and outlet channels, for guiding a check to and from said seat when the holder is respectively in different positions, the opposite walls of the inlet-channel being extended inwardly to form deflecting-points, substantially as specified.
10. A check-holder for the purpose named, having an inaccessible check-seat and communicating terminally open inlet and outlet channels, for guiding a check to and from said seat when the holder is respectively in different positions, the inlet-channel having communicating portions inclined in different directions to cause a check passing to the check-seat, to traverse a sinuous path and constituting means for preventing removal of the check through the inlet-channel, substantially as specified.
11. The combination with a mine-car, of an attached check-holder, and a communicating outlet-channel accessible to a seated check when the car is in an adjusted position, and means for preventing removal of the check when the car is in its normal position, substantially as specified.
12. The combination with a mine-car, of an attached holder having a check-seat visible through an inspection-opening through which a seated check cannot be removed, and inlet and outlet channels for guiding a check to and from said seat, respectively, when the car is in its normal and tilted positions, substantially as specified.
- In testimony that I claim the foregoing as my own I have hereto affixed my signature in the presence of two witnesses.
